UNITED STATES PATENT OFFICE.

OTTO E. MAUL, OF MOUNT VERNON, NEW YORK.

DESIGN FOR APPLIQUÉ TRIMMING FOR WEARING-APPAREL OR ARTICLE OF SIMILAR NATURE.

57,537.

Specification for Design.

Patented Apr. 12, 1921.

Application filed September 30, 1920. Serial No. 413,921. Term of patent 7 years.

To all whom it may concern:

Be it known that I, OTTO E. MAUL, a citizen of the United States, and a resident of Mount Vernon, in the county of Westchester and State of New York, United States of America, have invented a new, original, and ornamental Design for Appliquéd Trimming for Wearing-Apparel or Articles of Similar Nature.

Reference is to be had to the accompanying drawing in which—

Figure 1 is a side elevation of a piece

of appliquéd trimming embodying my new design; and

Fig. 2 is a cross section thereof.

I claim:

The ornamental design for appliquéd trimming for wearing apparel or article of similar nature, as shown.

OTTO E. MAUL.
